UNITED STATES PATENT OFFICE.

JOSEPH BARNES, OF NEW BEDFORD, MASSACHUSETTS, ASSIGNOR TO L. V. B. TENSION COMPANY, OF NEW BEDFORD, MASSACHUSETTS, A CORPORATION OF MASSACHUSETTS.

THREAD-TENSIONING MEANS.

Application filed March 21, 1925. Serial No. 17,253.

To all whom it may concern:

Be it known that I, JOSEPH BARNES, a citizen of the United States, residing at New Bedford, in the county of Bristol, State of Massachusetts, have invented a certain new and useful Improvement in Thread-Tensioning Means, of which the following is a specification, reference being had therein to the accompanying drawings.

10 The invention relates to tension devices such as those which are used for imparting the necessary tension to yarns, threads, and the like, in being wound, etc.

The invention has been designed, primarily, for application in connection with tension devices of the type of those shown, described, and claimed, in U. S. Letters Patent No. 1,356,026, dated Oct. 19, 1920, and No. 1,393,926, dated Oct. 18, 1921. Such tension devices comprise, essentially, a presser-lever, a presser carried by such lever and arranged to coact with a backing surface in connection with the head of the tension device; and a tension-weight applied to the lever and adjustable upon the lever to vary the degree of the pressure of the presser against a yarn or thread passing between the presser and the backing surface.

30 The invention comprises various novel combinations which are set forth in the claims at the close of this specification.

An illustrative embodiment of the invention is shown in the drawings, in which latter,—

35 Fig. 1 is a side elevation of a tension device comprising the said embodiment, together with its supporting bracket or stand, such view showing also a supply bobbin and a receiving spool.

40 Fig. 2 is a top view of the head portion of the tension device.

Fig. 3 is a sectional detail view of the supporting-head, presser-lever, and presser, the section being on line 3—3 of Fig. 2.

45 Fig. 4 is a sectional detail view of the presser-lever and weight, the section being on line 4—4 of Fig. 1.

Having reference to the drawings,—

50 1 is the head of the illustrated tension device, 2 is a presser-lever that is pivotally mounted upon the said head, at one side of the latter, by means of a pivot 3, and 4 is a presser that is pivotally mounted upon the said presser-lever by means of a pivot 5.

55 A tension-weight 6 applied to presser-lever

2 governs the pressure of the presser upon a yarn α passing between the presser and a backing surface 7 with which the head 1 is furnished. 8 is a yarn-guide with which the head is provided, in advance of the presser and in line therewith, and through which the yarn or thread passes on its way from the source of supply to and between the presser and the backing surface. The head is forked in advance of the guide 8 to facilitate the introduction of the yarn or thread into the guide.

The presser-levers of the two patents aforesaid are made of wire, the wire in each case having a number of bends to give the lever the required form, with one portion thereof adapted to constitute a journal which fits a bearing in the supporting head, a second portion thereof adapted to constitute a journal on which the presser is mounted pivotally and a third portion adapted to constitute a carrying arm for the tension-weight, etc. A presser-lever 2 constructed in accordance with the present invention is made of sheet material, usually metal, with a hole 21, Fig. 1, for the reception of a lever-pivot, a hole 22 for the reception of a presser-pivot, and a slot 23 providing for adjustable mounting of a tension-weight. The lever-pivot 3 is engaged with the head 1 and in the hole mentioned first; the presser-pivot 5 is engaged in the other hole; and the slot 23 is utilized for the attachment of the tension-weight 6 to the presser-lever, and for the adjustment of the said weight upon the lever with reference to the pivot 3 of the presser-lever to vary the effective leverage of the weight. The improved presser-lever may be made conveniently as a stamping.

The preferred mode of mounting the presser-lever upon the head of the tension device, constituting one of the features of improvement comprised in the invention, consists in fixedly connecting the pivotal stud 3 with the presser-lever 2 in such relation therewith as to project transversely therefrom, making the head with a transverse hole 11, Fig. 3, to serve as a presser-bearing, and entering the stud into the transverse hole 11 to serve as a journal. In this instance, one end of stud 3 is fixedly secured in the appropriate hole in the presser-lever, as by riveting the said end in the said hole. To retain the journal in the bearing and

- prevent accidental transverse displacement of the presser-lever and presser, a threaded axial hole is bored and tapped in the free end of the stud, and the stem of a flanged 5 screw 9 is screwed into the said hole, with the flange of the said screw engaged around the end of hole 11 at the side of head 1 opposite that at which the presser-lever is located.
- 10 The preferred mode of mounting the presser upon the presser-lever, constituting one of the features of improvement comprised in the invention, consists in fixedly attaching the pivotal stud 5 to the presser-lever 2 in such relation thereto as to project transversely from the presser-lever cross-wise of the backing surface of the head 1, and utilizing such stud as a journal upon which the presser may swivel in a plane at 15 right angles with the said backing surface. In this instance, one end of stud 5 is placed in one of the holes in the presser-lever and made fast therein, as by riveting such end, as in Fig. 3. In this instance, also, the presser is of the form presented in Patent 20 No. 1,393,926, it comprising a shoe 19 by which the presser is mounted upon the journal-stud 5, and a spring strip 20 which is attached at one end thereof to an extension 25 of shoe 19 and bent so as to extend beneath the shoe, between the shoe and the backing surface with which the presser coacts, from one end of the shoe to the other end thereof, where its free extremity is bent up close to 30 the latter end of the shoe. The acting portion of the spring strip is shown formed into transverse ribs 24, 24, to make contact with the backing surface or the yarn or thread passing between such surface and the shoe, as in Patent No. 1,393,926. The 35 shoe 19 is made of a strip of fairly stiff spring metal, folded upon itself with its two limbs close together, and shaped to form a bearing 25 for the reception of journal-stud 5. The presser is applied to the journal-stud by slipping the presser edgewise, 40 lengthwise of the stud, so that the stud shall enter the said bearing. The presser may be held from accidental lateral displacement 45 upon the journal-stud in any approved manner, but a further feature of improvement consists in providing against such accidental displacement by means of an enlarged shoulder 51 upon the stud 5 at a distance 50 from the presser-lever suitably proportioned to the width of the shoe 19 to enable such shoulder to be located alongside but outside the shoe. The bearing formed between the two limbs of the elastic shoe is slightly 55 smaller in diameter than the enlarged shoulder. As the said bearing is passed over the journal-stud, the shoulder spreads the two limbs apart somewhat. As the shoe completely passes the shoulder, the two limbs of 60 the elastic shoe close toward each other

around the smaller body of the journal-stud. The shoulder operates to prevent displacement of the shoe in the reverse direction under normal working conditions. Sufficient force exerted manually will enable the shoe to be removed from the journal-stud, and thereby disengaged from the presser-lever, when desired. The said smaller body of the journal-stud is shown as made barrel-shaped to provide for lateral rocking of the presser-shoe, as in my application for U. S. Letters Patent filed July 10, 1923.

Referring now to the improvement in the means of adjustably mounting the weight upon the presser-lever, the slot 23 in the presser-lever extends lengthwise of the presser-lever below the pivot 3, at both sides of the said pivot. The stem of the weight-securing screw 61 occupies the said slot, the portion of such stem which is within the slot being slabbed off at opposite sides thereof for engagement with the sides of the slot to prevent the screw from turning. The screw-head is lipped or flanged at the side of the presser-lever adjoining the head 1 of the tension device, for engagement with such side. A threaded hole 63 in the weight 6 receives the threaded stem of the screw 61. The weight 6 is applied to the projecting stem of the screw, at the outer side of the presser-lever, and is screwed up tightly against such side, so as to clamp the presser-lever firmly between the lips or flanges of the screw and the weight, to hold the weight at the point to which it has been adjusted. The slot 23 permits the weight to be shifted relative to pivot 3 to secure the desired effect of the presser upon the yarn or thread passing between the presser and the backing surface 7.

The backing surface 7 in the case of the embodiment of the features of the invention that is shown in the drawings is constituted by the top surface of a wear-plate that is let into a recess in the face of the head 1, as shown and described in Patent No. 1,393,926, aforesaid.

What is claimed as my invention is:—

1. A tension device of the character described comprising a head; a presser-lever of sheet-material formed with a hole for a lever-pivot, a hole for a presser-pivot, and a slot providing for adjustable mounting of a tension-weight; a lever-pivot engaged with the said head and in one of said holes; a presser-pivot engaged in the other hole; a presser mounted upon the presser-lever by means of the presser-pivot and cooperating with a backing surface in connection with the head; and a weight having securing means occupying said slot and adjustable along the same relative to the lever-pivot to vary the effective leverage of the weight.
2. A tension device of the character described comprising a head having a presser-

bearing, a presser-lever of sheet material having an attached lever-pivot occupying the said presser-bearing in the head, and an attached presser-pivot, and also having a slot 5 providing for adjustable mounting of a tension-weight; a presser having a bearing which fits upon said presser-pivot; a weight-securing screw occupying the said slot, flanged at one side of the presser-lever to engage with the latter at such side; and a tension-weight screwing upon the screw-stem at the other side of the presser-lever into engagement with the latter at such side.

3. A tension device of the character described comprising a head, a presser, a presser-carrying lever having an adjustment slot, a weight-securing screw occupying such slot, flanged at one side of the presser-lever to engage with the latter at such side, and a tension-weight screwing upon the screw-stem 15 at the other side of the presser-lever into engagement with the latter at such side, the slot permitting adjustment of the tension-weight relative to the lever-pivot to vary the effective leverage of the tension-weight.

JOSEPH BARNES.
